UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

PHONOGRAPH.

Application filed October 17, 1921. Serial No. 508,310.

To all whom it may concern:

Be it known that I, JOSEPH W. BISHOP, a citizen of the United States, residing at Muskegon, in the county of Muskegon and 5 State of Michigan, have invented certain new and useful Improvements in Phonographs, of which the following is a specification.

This invention relates to phonographs and 10 has for its principal object to provide a construction in which the needle in reproducing will travel along the same path with respect to the record as the needle did in recording.

Another object of the invention is to produce a construction whereby the needle will 15 travel along the radius of the record during reproduction.

Another object of the invention is to eliminate the customary tone arm and connected 20 parts, thereby enabling the phonograph mechanism to be made much more compactly and at a lower cost.

Further objects of the invention will become apparent as the description is read in 25 connection with the accompanying drawing showing a selected embodiment of the invention in which—

Fig. 1 is a fragmentary plan view illustrating the novel structure and a portion of 30 the record;

Fig. 2 is a longitudinal sectional view on the line 2—2 of Fig. 1;

Fig. 3 is an end elevation showing the needle and needle support; and

Fig. 4 is a fragmentary detail illustrating a modification.

In the drawing, 10 indicates a top plate or motor board, 11 a record table carrying a record 12, and adapted to be revolved by the 40 customary mechanism, not shown. A bracket 13 is secured to the bottom of the motor board and has a bifurcated end 14 provided with pivots 15 upon which is mounted a tubular member, or tone arm 16 equipped at its free end with a sound box 17. I have shown the tone arm as having a frustoconical sound passage 18 communicating with the interior of the sound box 17 which is secured to a flange 19 on the tone 45 arm. Within the sound box is the usual diaphragm 20 clamped between the tubes 21. The upper portion of the sound box 22 converges as indicated in Fig. 2, and has a U-shaped flange 23 to which is secured an upper 50 right 24, also U-shaped, and having at its

upper end the arms, or brackets 25 to which a yoke 26 is pivoted by screws 27 as indicated in Fig. 1. A pair of bars 28 are connected with the yoke 26 and carry at their opposite ends a horseshoe-shaped frame 29, best shown in Fig. 3. A spring 30 is suitably secured to the upper portion of the frame 29 and carries the needle support 31 having an angular needle socket 32 in which a needle 33 is adapted to be secured by 60 means of a screw 34. The needle support 31 is connected with one end of a rod 35, the opposite end of which is pivoted at 36 to an arm 37 of bell crank lever 38, having an arm 39 connected by a rod 40 with the diaphragm 70 20. The axis of the pivot 36 is co-incident with the axis of the screws 27 so that the bars 28 carrying the needle support can be freely swung about horizontal axis passing through the screws 27 without effecting the 75 position of the bell crank lever 38. The axis of the pivots 15 is at right angles to a radius of the record table 11, and therefore the swinging movement of the sound box and connected parts will be co-incident with the 80 radius of the record table. In order to prevent the weight of the moving parts from effecting the action of the needle, equalizing springs 41 are secured to the bracket 13 at 42 and engage lugs 43 on the tube 16. 85

In operation the tone arm and sound box are swung to the left in Fig. 2 until the needle 33 can be engaged with the record groove at the outside of the record, the springs 41 acting to equalize the weight of 90 the parts. As the record rotates, the needle traveling in the spiral groove gradually feeds toward the center of the table along the radius carrying with it all the parts supported by the pivots 15. The rods 35 and 95 40, and the bell crank lever 38 communicate the vibrations of the needle to the diaphragm 20 from which the sound vibrations pass down the frusto-conical passage 18 into the amplifier 44 which may be of any form 100 desired.

The angular form of the rod 40 permits me to use the arrangement of parts shown and still have clearance for the swing movement. A reversal of the lever and pivots 105 27 would make it possible to use a straight rod.

It will be clear from the foregoing description that the customary tone arm with all its complex connections is entirely elimi- 110

nated by the use of my invention, and all of the parts which replace the tone arm and sound box can be very compactly arranged so as to take up very much less room. It will also be obvious that the embodiment here shown can be manufactured at a very much lower cost than the phonographs at present in common use.

The construction illustrated in Figs. 1, 2 10 and 3 is intended to reproduce laterally cut records, but by providing the needle support with an arm 45, as indicated in Fig. 4, the device can be adapted to play hill and dale records. This arm may be made as an 15 integral part of the needle support, or as an attachment, as may be found most desirable.

I am aware that changes in the form and proportion of parts, and in the details of 20 construction of my invention may be made without departing from the spirit or sacrificing any of the advantages thereof, and I reserve the right to make all such changes as fairly fall within the scope of the following 25 claims.

I claim:

1. In a device of the class described, a sound box mounted to swing about a horizontal axis, a frame pivoted to said sound 30 box, a needle support carried by said frame and adapted to move along a radius of the record table, a record table adapted to support a record in the position to act upon a needle in said support, a diaphragm in said 35 sound box, and means pivotally connected to the sound box for connecting said needle support with said diaphragm.

2. In a device of the class described, a record table, a sound box pivoted to swing 40 about an axis at right angles to a radius of said record table, a frame pivotally connected with said sound box, a needle support carried by said frame and adapted to move along a radius of the record table, a diaphragm in 45 said sound box, and means for connecting said needle support with said diaphragm.

3. In a device of the class described, a record table, a sound box pivoted on an axis at right angles to a radius of said 50 record table, a diaphragm in said sound box, a needle support adapted to move along a radius of the record table, means carrying said needle support and pivotally connected with said sound box, and means including a 55 pivotal lever for operatively connecting said needle support with said diaphragm.

4. In a device of the class described, a record table, a sound box pivoted on an axis at right angles to a radius of said record 60 table, a frame pivotally connected with said sound box on an axis parallel to the pivotal axis of said sound box, a needle support carried by said frame and adapted to traverse a radius of the record table, a diaphragm in said sound box, and means for 65

connecting said diaphragm and said needle support.

5. In a device of the class described, a record table, a sound box pivoted on an axis at right angles to a radius of said record 70 table, a frame pivotally connected to said sound box on an axis at right angles to said record table, a diaphragm in said sound box, a needle support carried by said frame and adapted to move along a radius of the record 75 table, links connected to said diaphragm and said needle support, and a bell crank lever connected to said links.

6. In a device of the class described, a record table, a sound box pivoted on an axis 80 at right angles to a radius of said record table, a needle support pivotally connected with said sound box, and adapted to move along a radius of the record table, a diaphragm in said sound box, and means including links and a bell-crank lever for connecting said needle support with said diaphragm. 85

7. In a device of the class described, a motor board or the like, a rotatable record 90 table disposed above the motor board or the like, a pivotally mounted sound box disposed beneath the motor board or the like, the pivotal axis of the sound box being normal to the axis of rotation of the record 95 table, a needle adapted to engage a record on the record table, and means operatively connecting the needle to the sound box.

8. In a device of the class described, a motor board or the like, a rotatable record 100 table disposed above the motor board or the like, a sound box disposed beneath the motor board or the like, means for pivotally mounting the sound box to swing in a plane substantially coincident with the axis of rotation of the record table, a travelling needle adapted to engage a record on the record 105 table, and means operatively connecting the needle to the sound box.

9. In a device of the class described, a motor board or the like, a rotatable record table disposed above the motor board or the like, a pivotally mounted sound box beneath the motor board or the like and having a diaphragm therein, the pivotal axis of the sound box being normal to the axis of rotation of the record table, a frame, a needle support carried by the frame, and means operatively connecting the needle support with the diaphragm. 110

10. In a device of the class described, a motor board or the like, a record table disposed above the motor board or the like, a sound box disposed beneath the motor board or the like and having a diaphragm therein, means for pivotally mounting the sound box, a frame pivotally connected to the sound box, a needle support carried by the frame, and means operatively connecting the needle support with the diaphragm. 115

11. In a device of the class described, an apertured motor board, a record table disposed above the motor board, a sound box disposed beneath the motor board and having a diaphragm therein, means for pivotally mounting the sound box, a bracket rigidly secured to the sound box and projecting through the aperture in the motor board, a frame pivotally connected to the bracket, a needle support carried by the frame, and means operatively connecting the needle support with the diaphragm.

JOSEPH W. BISHOP.
